DEVICE FOR ASSEMBLING FURRING NAILS

Vernon A. Large, Oakland, Calif.

Application February 1, 1947, Serial No. 725,897

9 Claims. (Cl. 10—158)

1

This invention relates to automatic machinery and has for its principal object the provision of a machine adapted to produce furring nails, as are used in the building trades. This is accomplished by providing a machine adapted to receive quantities of nails and fiber discs at separate hoppers, arrange for the unit simultaneous delivery of nails and discs respectively at a common point, and cause the nails to pierce the discs as will be described herein.

I accomplish the above result by the machine illustrated on the accompanying drawings, forming a part hereof, in which:

Figure 1 is a side elevation of an embodiment of my invention.

Figure 2 is a top plan view of the oscillating hopper and its associated mechanism.

Figure 3 is a view showing the nail conveyer, and the trough and screw as seen from line 3—3 of Figure 1.

Figure 4 is a transverse section through the oscillating hopper and its driving mechanism, taken on line 4—4 of Figure 1.

Figure 5 is a longitudinal vertical section through the oscillating hopper.

Figure 6 is a transverse section through the nail conveyer, taken on line 6—6 of Figure 3.

Figure 7 is a transverse section through the nail trough and screw, taken on line 7—7 of Figure 3.

Figure 8 is a longitudinal vertical section through the nail driving assembly.

Figure 9 is a fragmentary section of the nail driving mechanism taken on line 9—9 of Figure 10.

Figure 10 is a top plan view of the assembly as shown on Figure 8.

Figure 11 is a top plan view of the nail extractor and its associated parts.

Figure 12 is a top plan view of the disc extractor and its associated parts.

Figure 13 is a top plan view of the nail positioning plate and its associated parts.

Figure 14 is a fragmentary section through the nail and disc guides, showing their relation with the rotatable members.

Figure 15 is a perspective view of a furring nail, the product of my invention.

Referring to the drawing in detail, it will be seen that my machine comprises four basic units consisting of the power driving mechanism, the disc conveying mechanism, the nail conveying mechanism and the nail driving mechanism. The units will be described in that order.

Power driving mechanism

A motor 20, suitably supported on the framework, indicated generally as 21, of the machine, is adapted to drive through a reduction bevel gear unit 22, and operate a shaft 23, mounted

2

on the side of the machine. The shaft 23, which is rotatably mounted in the gear box 22, at its lower end and in a pillow block 24, at its upper end, passes through a second bevel gear box 25, located near its lower end, and is geared to and operates a stub shaft 26, upon which is fixedly mounted, a pulley 27. The upper end of shaft 23, has fixedly mounted thereon, a sprocket 28, adapted to drive a second sprocket 29, by means of the connecting chain 30.

A transverse shaft 31, rotatably mounted in pillow blocks 32, has fixedly mounted thereon, pulleys 33, and 34, and bevel gear 35, and is adapted to be driven from the stub shaft 26, by means of pulleys 27, and 33, and the connecting belt 36. A second transverse shaft 37, mounted at the upper end of the machine and parallel to shaft 31, is rotatably supported in pillow blocks 38. Rotary motion is transmitted to shaft 37, by means of pulleys 34, and 39, and their connecting belt 40. Mounted on shaft 37, and adapted to be driven thereby, is a conveyor belt driving sheave 41.

From the foregoing it will be obvious that the shafts, as described, are all adapted to be driven simultaneously by one motor and their connecting power transmitting mediums.

Disc conveying mechanism

Connected at the uppermost part of frame 21, are two angles 42, which are transversely coplanar, and which slope forwardly and downwardly and terminate at their lower ends in bent feet forming portions 43. The angles 42, are bridged at their upper ends, for a portion of their length, by a plate 44, upon which is mounted an oscillating hopper 45, pivoted by means of a stud 46. The hopper 45, and the stud 46, are located on the longitudinal center line of the machine, and the hopper 45, which is of symmetrical construction, is adapted to oscillate between the extreme positions as indicated by center lines on Figure 2. The hopper 45, which is bottomless, comprises sides 47, preferably designed to diverge at their upper ends for convenience in loading, and which are connected by an angle 48. The angle 48, is provided with a hole 49, adapted to engage the stud 46, in pivotal relation.

Connecting sides 47, for the parallel portion of their length, is a plate 50, which is located downwardly, for the greater part of its length, from the upper edges of the sides 47, forming a recess 51. The plate 50, is preferably bent upwardly near its upper end, to give a funnel effect for convenience in loading. The upper edge of the plate 50, and the diverging portions of the sides 47, form an opening 52, through which the hopper is loaded with the fiber discs 53.

The space 54, enclosed on the sides by plates 47, on the top by plate 50, and on the bottom by

plate 44, upon which the hopper 45, is adapted to slide, is almost entirely closed at its forward end by a plate 55. Plate 55, terminates at its lower end short of the lower edges of sides 47, leaving an opening leading to a vertically restricted passage 56, bounded on the side by relatively narrow members 57, which are attached to, and extend forwardly from, the sides 47. The space 56, is closed at the top by a plate 58, lying parallel to plate 44, and spaced a distance therefrom greater than the thickness of the discs 53, but less than their diameter.

The lower edge of the plate 58, is of arcuate formation, and is concentric to stud 46. Secured to and extending across the lower end of plate 44, is an angle 59, of arcuate formation, complementary to the edge of plate 58. Angle 59, closes the forward end of the passage 56, except for an opening at the center which communicates with a relatively narrow channel shaped trough 60, just wide enough to permit the passage of single discs 53. The lower ends of the narrow members 57 and the lower edge of the plate 58 are adapted to bear against the upstanding leg of the angle 59, but are free to slide thereon when the hopper 45 is in motion.

The trough 60, which leads to the nail driving mechanism is preferably fitted with a wire 61, which extends for its entire length, and prevents the discs 53, from being displaced during transit.

Slidably mounted above the trough 45, on a pair of transverse parallel rods 62, is a reciprocating frame 63, consisting of a base plate 64, upstanding sides 65, and connecting reinforcing angles 66. The sides 65, are flanged at each end, and have secured thereto, pillow blocks 67, by means of which the reciprocating assembly is mounted on the rods 62. The rods 62, are secured to the frame of the machine by means of brackets 68. Secured to the under side of plate 64, are arcuate flanges 69, which extend downwardly into the space 51, and contact the inner sides 47, of the hopper 45, in driving relation.

The frame 63, is reciprocated by means of a disc 70, eccentrically mounted on the lower end of a shaft 71, which is driven by the sprocket 29, and chain 30, aforementioned. The shaft 71, is journalled in a pillow block 72, mounted on a transverse angle 73, secured to the frame 21, of the machine. The disc 70, is adapted to fit loosely between the sides 65, of the reciprocating frame 63, and rotate in contact therewith. Rotation of the disc 70, therefor, causes the frame 63, to reciprocate upon the rods 62. The motion of frame 63, is transmitted, by means of the flanges 69, to the hopper 45, which is caused to oscillate upon the stud 46.

Nail conveying mechanism

Supported within the framework 21, of the machine, is an open hopper 74, adapted to be loaded at its lower end with nails 75. The bottom of the hopper 74, in transverse section, slopes downwardly toward the upper run of an endless conveyer belt 76, which is fitted with spaced attachments 77. The belt 76, runs coincidental, in longitudinal relationship, with the bottom of the hopper 74, which is equipped with a relatively shallow V-shaped extending trough 78, as shown in section on Figure 6. The trough is formed with downwardly extending flanges 79, which serve to guide the belt 76, and also prevent the loss of nails through the space in which the upper run of the belt travels.

The belt 76, is driven by the aforementioned

sheave 41, and is supported at its lower end by an idler sheave 80, mounted on a shaft 81, which is journalled in pillow blocks 82. The belt 76, is adapted to travel in a direction that causes its top run to move upwardly, and thus convey nails from the hopper 74, and up the trough 78, which extends to the end of the top run of the belt. Located beneath the sheave 41, and being adapted to receive the nails as they fall from the belt 76, is a chute 83, which slopes downwardly to, and connects with, the upper end of a trough 84, shown in section in Figure 7.

Rotatably mounted in the trough 84, is a conveyer screw 85, which is driven by a bevel gear 86, adapted to mesh with the aforesaid gear 35, mounted on the shaft 31. The trough 84, has a longitudinal slot 87, in the bottom thereof which extends from a point adjacent the upper end of the screw 85, to the lower end 88, of the trough 84, said lower end being located in, and communicating with, the hopper 74. The sweeping action of the flight of the rotating screw causes the nails to fall through the slot 87, however, they are prevented from falling all the way through by angles 89, secured to the under side of the trough 84, in offset relation with the edges of the slot 87. The angles 89, support the nails by the under side of the heads, while the body portion is suspended between the adjacent faces of the angles. Angles 89, extend downwardly through the lower end of hopper 74, and connect with the nail driving mechanism.

Nail driving mechanism

35 Bridging the angles 42, near the lower ends thereof and secured thereto, is a base plate 90 formed with a centrally located boss 91 and an upstanding stud 92, upon which is journalled a rotatable head 93. The plate 90 has mounted thereon, adjacent its outer edges, a pair of upstanding brackets 94, to which are attached pillow blocks 95, mounting shaft 96. Fixedly mounted upon shaft 96, is a bevel gear 97, a concentric roller 98 and a pulley 99, adapted to 45 drive the shaft in cooperation with a motor 100 and its pulley 101 and belt 102.

The upper end of the stud 92, is supported by a strap 103, which is secured to one of the brackets 94. A collar 104, is located on the stud 50 92, on its reduced upper end, and the strap 103, is securely clamped to this collar by means of the nut 105. The collar 104, also forms a shoulder which holds the rotatable head 93, in its place on the stud 92.

55 The rotatable head 93, is provided at its upper end with a bevel gear 106, which meshes with gear 97, and is driven thereby. It is also provided with a pair of annular concentric flanges 107 and 108, which are spaced apart, and are designed 60 with a plurality of drilled bosses, 109 and 110, respectively, adapted to receive nail driving plungers 111, in sliding relation. The plungers are maintained in their normal position by means of compression springs 112, acting against the 65 collars 113, which are secured to the plungers 111, by means of pins 114. Four plungers are illustrated; however, the machine can be equipped with a larger or smaller number of plungers, and still function satisfactorily.

70 Firmly secured to the rotatable head 93, in the order named and commencing with the upper member, are a nail extractor 115, a nail positioning plate 116, a fiber disc extractor 117, and a roller thrust bearing 118, adapted to rotate 75 against the face of the boss 91, on the base plate

90. The nail extractor 115, consists of a flat circular plate with a centrally located hole 119, adapted to maintain it in concentric relation with the head 93. Holes 120, are provided to receive the fastening bolts 121. A boss 122, is formed on the under side of the extractor in order to provide clearance for the projecting portion of the vertical leg of angle 123, which is notched out, at the delivery end, to clear the extractor 115. Located in the thin portion of the extractor 115, are four holes 124, which are each connected to the periphery by an arcuate slot 125, as illustrated on Figure 11. The inner sides of the slots 125, are faired into the periphery of the extractor 115, in order to provide a smooth cam-like surface. The holes 124, which are so positioned as to be in assembled alignment with the plungers 111, are sufficiently large to receive the plungers, and also to allow the nails 75, to pass completely through them; the slots 125, however, while freely admitting the body of the nail, are not sufficiently wide for the head to pass through.

The nail positioning plate, which is also designed to be in alignment with the head 93, and the plungers 111, is provided with the holes 119, and 120. The nail positioning features comprise four spaced holes 126, sufficiently large to admit the body of the nail 75, and counter-drilled for a portion of their depth to enlarge them sufficiently to receive the nail head. The bottom of the counter-drilled portion of the hole is countersunk, forming a funnel like opening which serves to guide the point of the nail into the smaller hole. As shown in Figs. 13 and 14, the holes 126, are opened radially to the periphery of the member 116, in order that the finished nails can be withdrawn. The nail positioning plate 116 shown in the detail in Fig. 13, is also formed with a boss 127, on the underside thereof. The fiber disc extractor 117, is also equipped with the aligning and fastening holes 119 and 120. It comprises a circular plate, the lower half of which is of slightly reduced diameter. Four flat bottomed holes 128, are drilled in the upper portion, and are milled through the edge of the plate to form a hook 129, with the outer connecting point, and a faired, cam-like surface 130, tangent to the inner side as shown on Figure 12. The bottom of the milled section forms a ledge 131, which supports the fiber discs 53, as they are drawn into place. Slots 132, which are in alignment with the circular portion of the milled recesses are provided to receive the points of the nails 75.

Elements 93, 115, 116, 117 and 118, are securely attached together by means of bolts 121, and are adapted to rotate upon stud 92, as a unit, in a clockwise direction as viewed from the top. Bridging the brackets 94, and secured thereto, is a transverse angle 133, adapted to support an internal cam member 134, having an opening 135, which, at its entrance, coincides with the upper rounded ends of the plungers 111. The internal cam member 134, is so positioned that the opening 135, sloping downwardly will start the downward motion of the plunger 111, and bring it into position to pass under the roller 98, with a maximum of smoothness of operation. After leaving the cam member 135 the rotation of the head 93 brings successively the tops of the plungers 111 under the roller 98 which presses them downwardly so that the lower end of each plunger bears upon the nail 75 and drives the same through the disk 53 located thereunder.

Extending across the angles 42, adjacent the base plate 90, and parallel thereto, is a transverse angle 136, supporting a plate 137, to which is attached the nail and fiber disc feeding conveyors. The fiber disc trough 60, is supported at its lower end by the plate 137, and terminates just clear of the fiber disc extractor 117, as shown on Figure 12. The bottom of the trough 60, coincides with the ledge 131, allowing the discs to pass freely thereon. A spring held trigger 138, holds the discs in place as they move forward onto the ledge 131. A pivoted arcuate guide member 139, held in place by a spring urged plunger 140, in block 141, serves to hold the discs in place until they pass under the roller 98, and are pierced by the nails 75. Block 141, which is attached to the base plate 90, as shown on Figure 14, contains an upper and a lower plunger 140, which are held in the protruding position by springs 142, locked in place by headless set screws 143.

Referring to Figure 11, the angles 59, connect with angles 123, which are supported by plate 137, and extend down to the nail extractor 115. Angles 123, are maintained the correct distance apart by cross members 144, and a guide 145, is also provided at the point where angles 89, and 123, butt together. The horizontal flange of the slot facing angle 123, projects a short distance, and overlaps the extractor, while the vertical flange has a projecting portion as aforementioned. These projecting portions, coacting with the spring held trigger 145, hold the nail 75, in position as it is drawn into the slot 125.

With reference to Figure 13, the nail positioning plate 116, is equipped with a pivoted arcuate guide 147, similar to guide 139. The guide 147, however, is designed with an upstanding flange 148, and a beveled portion complementary to the edge of element 116. The guide 147, is also equipped with a spring actuated trigger 149, which serves to kick the nails in place in the slots 126. Guides 139, and 147, are pivoted on a common shoulder stud 150, screwed into the base plate 90, as shown on Figure 8.

The finished furring nails are ejected from the machine by means of a trigger 151, pivoted on a shoulder stud 152, screwed into the base plate 90. A tension spring 153, maintains the free end of the trigger 151, in contact with the edge of the reduced portion 127, of element 116.

Operation

Fiber discs are fed into the oscillating hopper 45, and nails are fed into the hopper 74; the motors 20, and 100, are then started. The fiber discs are tumbled and agitated and are eventually turned onto one of their flat sides and are then able to slide into the restricted passages 56. As the hopper oscillates backward and forward, the discs pass out, one by one, through the opening in angle 59, into the trough 60, and down to the nail driving mechanism.

Simultaneously with this operation, the nails in the hopper 74, are being carried upward, by the conveyor belt 76, and are dumped into the chute 83, where they slide down into the trough 84. The nails are swept into the slot 87, by the action of the screw 85, as has been described, and slide down between the angles 89 to the nail driving mechanism. Any nails which fail to fall into the slot fall back into the hopper and are recirculated; sufficient nails, however, fall into the slot to ensure a continuous feed to the nail driving mechanism.

Nails and disc are extracted simultaneously by

the rotating members 115, and 117, respectively, the nails passing into the member 116 and being driven into the discs 53, by plungers 111, as they pass through the cam 134, and under the roller 98. The finished product, as shown on Figure 15, is ejected from the rotating assembly by means of the trigger 151.

From the foregoing it will be apparent that I have devised a new and useful machine especially adapted to the economic production of a necessary commodity, and while I have disclosed a preliminary embodiment of my invention, it will be understood that modifications may be made within the spirit and scope of the appended claims.

I claim:

1. In a machine for producing furring nails, a frame, a rotating head on the frame, a nail feeding chute leading to the periphery of the upper portion of said head, a disk feeding chute leading to the periphery of the lower portion of said head, said head containing a plurality of circumferentially spaced substantially vertical holes, the upper portion of each hole being spaced from the periphery of said head, said head having slots extending from the upper portion of each hole to the periphery of the head, said nail chute comprising means for holding a nail in the path of said slots so as to feed a nail into each slot and said slots comprising means for coacting with the end of said nail chute to guide said nail into said hole during the rotation of said head; the lower portion of each of said holes being formed into a hook recess open to the head periphery, a peripheral guide surface leading from the head periphery to each hook recess to guide a disk from said disk chute into the recess, a ledge in each recess to support said disk in registry with said hole under said nail, the middle portion of each hole being restricted for centering the nail with respect to said disk in said recess and being open to the periphery of said head, arcuate guide members substantially stationary relatively to said rotating head to cover the peripheral open sides of the hole located opposite said guide members for retaining said nail and disk in aligned position, a plunger device for extending a plunger into the top of the hole opposite said guide members and means for actuating said plunger to push the nail into the aligned disk.

2. In a machine for producing furring nails, a frame, a rotating head on the frame, a nail feeding chute leading to the periphery of the upper portion of said head, a disk feeding chute leading to the periphery of the lower portion of said head, said head containing a plurality of circumferentially spaced substantially vertical holes, the upper portion of each hole being spaced from the periphery of said head, said head having slots extending from the upper portion of each hole to the periphery of the head, said nail chute comprising means for holding a nail in the path of said slots so as to feed a nail into each slot and said slots comprising means for coacting with the end of said nail chute to guide said nail into said hole during the rotation of said head; the lower portion of each of said holes being formed into a hook recess open to the head periphery, a peripheral guide surface leading from the head periphery to each hook recess to guide a disk from said disk chute into the recess, a ledge in each recess to support said disk in registry with said hole under said nail, the middle portion of each hole being restricted for centering the nail with respect to said disk in said recess and being open to the periphery of said head, arcuate guide members substantially stationary relatively to said rotating head to cover the peripheral open sides of the hole located opposite said guide members for retaining said nail and disk in aligned position, a plunger on the head aligned with each hole, and a plunger actuating means at said guide members to move the plunger into said hole for pushing the nail into the aligned disk.

3. In a machine for producing furring nails, a frame, a rotating head on the frame, a nail feeding chute leading to the periphery of the upper

portion of said head, a disk feeding chute leading to the periphery of the lower portion of said head, said head containing a plurality of circumferentially spaced substantially vertical holes, the upper portion of each hole being spaced from the periphery of said head, said head having slots extending from the upper portion of each hole to the periphery of the head, said nail chute comprising means for holding a nail in the path of said slots so as to feed a nail into each slot and said slots comprising means for coacting with the end of said nail chute to guide said nail into said hole during the rotation of said head; the lower portion of each of said holes being formed into a hook recess open to the head periphery, a peripheral guide surface leading from the head periphery to each hook recess to guide a disk from said disk chute into the recess, a ledge in each recess to support said disk in registry with said hole under said nail, the middle portion of each hole being restricted for centering the nail with respect to said disk in said recess and being open to the periphery of said head, arcuate guide members substantially stationary relatively to said rotating head to cover the peripheral open sides of the hole located opposite said guide members for retaining said nail and disk in aligned position, a plunger device for extending a plunger into the top of the hole opposite said guide members and means for actuating said plunger to push the nail into the aligned disk.

4. In a machine for producing furring nails, a frame, a rotating head on the frame, a nail feeding chute leading to the periphery of the upper portion of said head, a disk feeding chute leading to the periphery of the lower portion of said head, said head containing a plurality of circumferentially spaced substantially vertical holes, the upper portion of each hole being spaced from the periphery of said head, said head having slots extending from the upper portion of each hole to the periphery of the head, said nail chute comprising means for holding a nail in the path of said slots so as to feed a nail into each slot and said slots comprising means for coacting with the end of said nail chute to guide said nail into said hole during the rotation of said head; the lower portion of each of said holes being formed into a hook recess open to the head periphery, a peripheral guide surface leading from the head periphery to each hook recess to guide a disk from said disk chute into the recess, a ledge in each recess to support said disk in registry with said hole under said nail, the middle portion of each hole being restricted for centering the nail with respect to said disk in said recess and being open to the periphery of said head, arcuate guide members substantially stationary relatively to said rotating head to cover the peripheral open sides of the hole located opposite said guide members for retaining said nail and disk in aligned position, a plunger on the head aligned with each hole, and a plunger actuating means at said guide members to move the plunger into said hole for pushing the nail into the aligned disk.

5. A machine for producing furring nails comprising a first trough adapted to pass through a single row of nails, a second trough adapted to pass through a single row of disks; a first circular plate rotatable relatively to said first trough and having a plurality of holes therein large enough to pass the nail through, each hole being connected with the periphery of said plate by a comparatively narrow slot; a second circular

plate attached to the first one and rotating therewith and having a plurality of holes in the periphery thereof, said holes being in alignment with the first mentioned holes and being large enough to admit the body of the nail, said last mentioned holes being radially open and adapted to receive the nails from the first mentioned holes and position the same; a third circular plate attached to the second mentioned plate and rotating therewith and having a plurality of holes therein aligned with the above mentioned holes and being large enough to admit the body of the nail, said third plate having peripheral portions thereof formed into recesses, located over said last mentioned holes, a device to guide the disks from the second trough into said recesses in position of alignment with the nails retained by the second circular plate; means for holding said nails and disks in their respective holes and recesses; means for driving nails through the respective aligned disks, and means for ejecting the furring nails.

6. A machine for producing furring nails comprising a first trough adapted to pass through a single row of nails; a second trough adapted to pass through a single row of disks; a first circular plate rotatable relatively to said first trough and having a plurality of comparatively narrow slots each leading from the periphery of said plate to a hole large enough to pass the nail through, each of said slots passing under said first trough and engaging a nail hanging from said first trough and guiding the nail from said trough and into said hole; a second circular plate located under the first one and rotating therewith and having a plurality of holes aligned with the first mentioned holes and large enough to receive the body of the nail; a third circular plate and rotating therewith and located under the second plate and rotating therewith having a plurality of holes aligned with the first and second mentioned holes and large enough to admit the body of the nail; a device actuated by the rotation of said third plate for transferring singly the disks from the second trough over the last mentioned holes in positions of alignment with the respective nails; means for holding said nails and disks in position of alignment; a rotary head located above said plates and attached thereto, a plurality of plungers in said head each of which is in alignment with the holes in the first circular plate, means for successively forcing said plungers downwardly onto said nails to drive the same into the disks thereunder; and means for ejecting the furring nails from the machine.

7. In a machine for producing furring nails, a frame, a rotating head on the frame, a nail feeding chute leading to the periphery of the upper portion of said head, a disk feeding chute leading to the periphery of the lower portion of said head, said head containing a plurality of circumferentially spaced substantially vertical holes, the upper portion of each hole being spaced from the periphery of said head, said head having slots extending from the upper portion of each hole to the periphery of said head, said nail chute holding a nail in the path of said slots so as to feed a nail into each slot and said slots comprising means for coating with the end of said nail chute to guide said nail into said hole during the rotation of said head; the lower portion of each of said holes being formed into a hook recess open to the head periphery, a peripheral guide surface leading from the head periphery

to each hook recess to guide a disk from said disk chute into the recess, a ledge in each recess to support said disk in registry with said hole under said nail, the middle portion of each hole being restricted for centering the nail with respect to said disk in said recess and being open to the periphery of said head, arcuate guide members substantially stationary relatively to said rotating head to cover the peripheral open sides of the hole located opposite said guide members for retaining said nail and disk in aligned position, a plunger on the head aligned with each hole, and a plunger actuator at said guide members to move the plunger into said hole for pushing the nail into the aligned disk, and an ejector device adjacent the head periphery beyond said guide members and in the path of the assembled furring nail to withdraw the furring nail from said hole during the rotation of said head.

8. In a machine for producing furring nails, a frame, a rotating head on the frame, a plurality of circumferentially spaced holes in said head, a plunger carried on said head above each hole being reciprocable into and out of the opposite hole, the lower portion of each hole being open toward the head periphery to permit lateral insertion of a disk into the hole, a relatively stationary nail feeding chute leading to the top of the holes in sequence as the head is rotated, the upper portion of each hole being spaced from the periphery of said head, said head having slots extending from the upper portion of each hole to the periphery of the head and being adapted to guide a nail from the nail feeding chute into the adjacent hole, a relatively stationary disk feeding chute leading to the lateral open side of the hole being carried past said disk feeding chute as the head is rotated for inserting a disk in advance of and below the insertion of said nail into each hole, said lower portion comprising disk-seating means to support said disk in registry with said hole under said nail, a relatively stationary plunger actuator above said head following said chutes with respect to the direction of rotation of said head to move the plunger for driving the nail into the aligned disk, and an ejector means following the plunger actuator location with respect to the direction of rotation of said head to remove the assembled furring nail through the open side of the lower portion of the hole as the head is rotated.

9. In a machine for producing furring nails, a rotating head having a plurality of circumferentially spaced holes, a plunger aligned with the top of each hole and moving aligned with respect to the holes, a relatively stationary feeding device, a relatively stationary plunger actuating device spaced circumferentially from the feeding device in the direction of rotation of said head, a relatively stationary ejector device spaced circumferentially from the plunger actuating device in the direction of rotation of said head, the lower portion of each hole being laterally open to the periphery of the head to permit lateral insertion of a disk, said feeding device including a nail chute above the top of the opposite hole, the upper portion of each hole being spaced from the periphery of said head, said head having slots extending from the upper portion of each hole to the periphery of the head and being adapted to guide a nail from the nail chute into the top of the hole, a disk chute to feed a disk into the laterally open lower portion of the adjacent hole below said nail, said lower

11

portion comprising disk-seating means to support said disk in registry with said hole under said nail, said plunger actuating device engaging each plunger brought to it by said head for moving said plunger into said hole and driving said nail through said disk and into the laterally open portion of the hole; and said ejector device being in the path of the assembled furring nail for urging the furring nail peripherally outwardly from said lower open portion of the hole.

VERNON A. LARGE.
